UNITED STATES PATENT OFFICE.

EPPA H. RYON, OF WORCESTER, MASSACHUSETTS, ASSIGNOR TO CROMPTON & KNOWLES LOOM WORKS, A CORPORATION OF MASSACHUSETTS.

NARROW-WARE LOOM.

SPECIFICATION forming part of Letters Patent No. 781,967, dated February 7, 1905.

Application filed June 18, 1904. Serial No. 213,074

To all whom it may concern:

Be it known that I, EPPA H. RYON, a citizen of the United States, residing at Worcester, in the county of Worcester and State of Massachusetts, have invented certain new and useful Improvements in Narrow-Ware Looms, of which the following is a specification.

My invention relates to narrow-ware looms or looms for making ribbon, tape, &c., in which two or more banks of shuttles are used; and my invention particularly relates to looms for weaving ribbon, tape, &c., with two or more different colors or different sizes of yarn.

The object of my invention is to improve upon the construction of narrow-ware looms of the class referred to as ordinarily made.

My invention consists in certain novel features of construction of my improvements, as will be hereinafter fully described.

I have only shown in the drawings sufficient parts of a narrow-ware loom with five banks of shuttles of the class referred to to enable those skilled in the art to which my invention belongs to make and use the same.

Referring to the drawings, Figure 1 is an end view of a loom-frame and of my improvements combined therewith looking in the direction of arrow *a*, Fig. 2. (Some of the parts at the left are broken away.) Fig. 2 is a front view of the parts shown in Fig. 1 looking in the direction of arrow *b*, same figure. Fig. 3 is a sectional view showing some of the parts shown in Fig. 2 detached. Fig. 4 is a section on line 4-4, Fig. 3, looking in the direction of arrow *c*, same figure. Fig. 5 shows some of the parts shown at the left in Fig. 1 detached. Fig. 6 is a front view of one end of the lay-frame, showing partially in section the shuttle-rails, the gears, and the racks for moving

the shuttles, looking in the direction of arrow *d*, Fig. 7; and Fig. 7 is a section on line 7-7, Fig. 6, looking in the direction of arrow *e*, same figure. Figs. 3 to 7, inclusive, are shown on an enlarged scale.

In the accompanying drawings, 1 is the loom side or frame.

2 is the upper cylinder-gear, 3 the lower cylinder-gear, 4 the vibrator-gears, 5 the vi-

brator-lever, operated by the pattern-chain 5', and 6 the vibrator-connectors, of the well-known Knowles head-motion shown and described in United States Letters Patent No. 134,992. The vibrator-connectors 6 (three in number) are in this instance connected with three levers 7, 8, and 9, pivotally mounted on 55 a stud 10. The lever 7 is of angle shape and is connected by a link 7' with one arm of an angle-lever 7", pivoted at 11 on one arm of an angle-lever 8'. The other arm of the angle-lever 7" is pivotally connected with a stud 12. 60 The lever 8 has pivotally mounted on its lower end at 8" an angle-lever 8', one arm of which is connected by the link 9' with one arm of the angle-lever 9, pivoted on the stud 10. The other arm of the angle-lever 8' carries 65 the stud 11, on which is pivoted the angle-lever 7", as above stated. By means of the three levers 7, 8, and 9 are given through intermediate mechanism the five positions as ordinarily required in a five-shuttle-box loom. 70 Said three levers 7, 8, and 9 are in this instance used to raise and lower the shuttle-rails, mounted on the lay-frame in any usual way and carrying the narrow-ware shuttles and their operating racks and pinions into 75 five different positions and also to communicate to the shuttles a longitudinal movement corresponding to said positions, as will be hereinafter described. In the drawings I have shown one position of the three levers 80 7, 8, and 9 and their connections, which position gives to the shuttle-rails the fourth position, or the second position from the highest position, and moves the second row of 85 shuttles from the bottom by their operating mechanism to weave in the fabric the color carried by said shuttles.

The stud 12 is that part of the mechanism which has communicated to it through the levers 7, 8, and 9 five different positions, and 90 said stud 12 is connected through intermediate connections with the shuttle-rails to communicate to them the five different positions communicated to said stud 12. The stud 12 is connected by a link 13 with one arm of a lever 14, centrally pivoted on a stud 15. The

stud 12 is also connected by a link 16 with the upper forked end 17' of a lever 17, pivoted at its lower end on a bracket 18. The forked lever 17 engages and operates a yoke 19' in a 5 grooved collar 19, fast on the sliding shaft 20, which shaft has fast thereon the two partial gears 21 and 22, having teeth thereon, and also the plain portion or dwell-section, and also has fast thereon the two check or dwell 10 drums 23 and 24, which extend over the five cams 25, 26, 27, 28, and 29, loosely mounted on the stud 30. The gear 21 is adapted to engage and rotate the four cams 25, 26, 27, and 28, while the gear 22 is adapted to engage and 15 rotate the cam 29. Each of the cams 25, 26, 27, 28, and 29 are in this instance provided with four separate series of teeth on their periphery (see Fig. 3) and an intermediate plain portion or dwell-section, which is concaved to 20 engage the convex surface of the drum-wheels 23 and 24. The operating-gears 21 and 22 are provided with enlarged teeth at each end of the teeth thereon which mesh with the teeth on the cams, and said enlarged teeth engage the ends 25 of the plain portions on the cams to commence to rotate the cams. Through the rotation of the five cams 25, 26, 27, 28, and 29 the proper movement is communicated through intermediate mechanism to the five banks of shuttles 30 to correspond with the movement of or the raising and lowering of the shuttle-rails carrying the shuttles. Each of the cams 25, 26, 27, 28, and 29 has a cam-groove 31 therein, (see Fig. 3,) which receives a roll 32' on a lever 32, pivoted on a rod 33. The lower end of each lever 32 is connected by a connector 34, adjustable as to its length with the lower end of a lever 35. Each lever 35 preferably has a stud 35' at its lower end, which is detachably connected with an open-end slot 34' at the end of the connector 34, so that the connectors 34 can be readily disengaged from the levers 35 for any purpose.

Each lever 35 has a longitudinal slot 35'' therein, through which extends a rod 36, which forms the pivot of the levers 35. The rod 36 extends at each end into and is adjustably held in a vertical slot 37' in the two uprights 37, connected at their upper ends with the end of 50 the shuttle-rails or the sheave-frame. The lower ends of the uprights 37 are fast to the cross-bar 37'', having a stud 37''' thereon. On the pivot-rod 36 are collars 36' to hold the levers 35 in their proper position thereon. 55 The upper end of each lever 35 is connected by a link 38 with a block 39, supported and having a reciprocating movement between the bars 39'. Each block 39 has attached thereto a strap 40, which passes around four pulleys 60 or sheaves 41, suitably supported, and has each end secured to an extension 42 on a rack-bar 43 to communicate a longitudinal motion to said rack-bar in each direction and through the pinions 44 (shown in Fig. 6) communicate 65 a motion to the shuttles 45 to cause them to

pass through the shed in front of the reed 46, carried on the shuttle-rails, in the usual and well-known way.

Cords 48, connected at one end to the connectors 34, pass over pulleys 49 on a stud 50 70 on a stand 51 and are attached at their other ends (not shown) and furnish means for the operator to raise each connector 34 and disengage it from its lever 35.

The shaft 20, carrying the cam-operating 75 gears 21 and 22, has a rotary motion communicated thereto through a gear 52, splined on the shaft 20 to allow said shaft to slide through it, and driven by a gear having a bevel-gear 53 attached thereto and in mesh with a 80 bevel-gear 54, fast on the lower end of an upright shaft 55. On the upper end of the shaft 55 is a bevel-gear 56 in mesh with a bevel-gear 57 on the face of a gear 58 on a stud 59. The gear 58 is in mesh with a gear 60, driven 85 by a gear 61, fast on a shaft 62, mounted in a sleeve 62' and carrying the driving-belt pulley 63 and the pulley 64, loose on said shaft 62, which receives the driving-belt (not shown) when it is shipped from the fast pulley 63. 90

Referring now to the centrally-pivoted lever 14, already described, the other arm of said lever is connected by a link 68 with an arm 69, fast on the rock-shaft 70. At the end of the rock-shaft 70 is fast an arm 71, which is 95 pivotally connected by a stud 71' with the upper end of a link 70'. The lower end of the link 70' has a hole therethrough to receive the stud 37'' on the bar 37''. The outer end of the stud 37'' extends into and is guided by a vertical slot 72' in the stand 72. (See Fig. 1.) Also fast on the rock-shaft 70 is one of a series of arms 73, pivotally connected at its outer end with the lower end of a connector or rod 74. The upper end of the connector 74 is 105 pivotally connected with a stud 74' on a collar 75, adjustably secured by a set-screw 76 on the rod 77, which is secured at its upper end to the lower side of the shuttle-rails and extends at its lower end through a guide or bearing 78, secured to the lay-sword 79', which is pivotally mounted at its lower end and carries at its upper end the lay 79. 110

A connector 80, attached to the lay 79 at one end and to a crank (not shown) at its other end in the well-known manner, communicates a swinging motion to the lay and the shuttle-rails from the crank on the driven shaft 82 in the usual way. A gear 83, fast on the shaft 82, meshes with a gear 84 and through gear 85 115 drives the upper cylinder-gear 2.

From the above description, in connection with the drawings, the operation of my improvements will be readily understood by those skilled in the art, and briefly is as follows: As the pattern-chain 5' revolves the three compound levers 7, 8, and 9 are moved, according to the indications of the pattern-surfaces, through the vibrator-levers 5, the vibrator-gears 6, and the connectors 7, operated by 120 125 130

the upper and lower cylinder-gears 2 and 3 in the usual way. The movement of the three levers 7, 8, and 9, according to the indications of the pattern-surfaces, is communicated to the stud 12 to move said stud into five different positions. The movement of the stud 12 is communicated through intermediate connections, consisting of the link 13, lever 14, link 68, arm 69, rock-shaft 70, and arms fast 10 on said rock-shaft, to give an up-and-down motion to the shuttle-rails and the shuttles and their operating mechanism to bring each of the five rows of shuttles at the proper time into a position at the front of the reed to carry 15 the filling through the shed. At the same time the movement of the stud 12, through the link 16, lever 17, sliding shaft 20, the partial gears 21 and 22 are moved into position to engage and rotate one of the cams 31, to 20 cause, through intermediate mechanism, consisting of the levers 32, connectors 34, levers 35, link 38, and blocks 39, a reciprocating movement to the belt 40, attached to the rack-bars 43, to cause a longitudinal motion of each 25 rack-bar, to operate the row of shuttles which is in position in front of the reed, to carry the filling through the shed.

The advantages of my improvements will be readily appreciated by those skilled in the 30 art.

I employ the well-known "Knowles head-motion" ordinarily used for operating the shuttle-boxes, for raising and lowering the shuttle-rails, carrying the shuttles and their 35 operating mechanism, and for moving the racks to operate the pinions to move the shuttles. I have shown in the drawings five banks of shuttles; but it will be understood that two or more banks of shuttles may be used.

40 It will be understood that the details of construction of my improvements may be varied, if desired.

Having thus described my invention, what 45 I claim as new, and desire to secure by Letters Patent, is—

1. In a loom of the class described, the combination with mechanism for raising and lowering the shuttle-rails carrying the shuttles, and mechanism for operating the shuttle racks 50 and pinions to communicate longitudinal motion to the shuttles, of one controlling mechanism for operating and regulating the operation of each of said mentioned mechanisms, substantially as shown and described.

55 2. In a loom of the class described, the combination with a pattern-surface, vibrator-levers, vibrator-gears, upper and lower cylinder-gears, vibrator-connectors, compound levers, and the shuttle-rails carrying the shuttles, and 60 their operating mechanism, of connections, intermediate the shuttle-rails and the operating mechanism of the shuttles, to communicate from the compound levers, the different positions of the shuttle-rails in a vertical 65 plane, and the movement of the operating

mechanism of the shuttles in the desired horizontal plane, substantially as shown and described.

3. In a loom of the class described, the combination with a pattern-surface, vibrator-levers, vibrator-gears, upper and lower cylinder-gears, vibrator-connectors, and compound levers, of a stud connected with said levers and operated thereby, to be moved into different positions according to the indications 75 of the pattern-surface and connections from said stud to the shuttle-rails, to raise and lower the shuttle-rails according to the position of said stud, and connections from said stud to the shuttle-racks, to move the shuttle-racks and operate the shuttles, substantially as shown and described.

4. In a loom of the class described, the combination with a pattern-surface, vibrator-levers, vibrator-gears, upper and lower cylinder-gears, vibrator-connectors, and compound levers, of a stud connected with said levers, and operated thereby, to be moved into different positions according to the indications of the pattern-surface, and connections from 85 said stud to the shuttle-rails, to raise and lower the shuttle-rails according to the position of said stud, and connections from said stud to the shuttle-racks to move the shuttle-racks and operate the shuttles, said connections comprising a longitudinal sliding shaft, partial gears fast thereon, cams engaged by said gears, cam-levers operated by said cams, connectors to pivoted levers, and said pivoted levers connected with and operating belts connected with the shuttle-racks, substantially 90 as shown and described.

5. In a loom of the class described, a series of shuttles, shuttle-racks to operate said shuttles, rotary cams having alternate teeth and 105 dwell-sections on their peripheries, connections between said cams and said shuttle-racks, a sliding shaft having a gear with dwell-section thereon to mesh with the teeth and engage the dwell-sections on said cams, and means to rotate said sliding shaft, and to move 110 it longitudinally, to operate any one of the said cams, to move the shuttle-racks, substantially as shown and described.

6. In a loom of the class described, shuttle-rails, a slide, a guide for said slide connected to or fast on said shuttle-rails, a shuttle-operating rack-rod, a flexible connection thereto, and means to operate said slide to move the 115 rack-rod longitudinally in either direction, substantially as shown and described.

7. In a loom of the class described, shuttle-rails, a slide, a guide therefor, a shuttle-operating rack-rod, connections between said slide and said rack-rod, and means to operate the 120 said slide, said means consisting of a rotating cam and intermediate connections, substantially as shown and described.

8. In a loom of the class described, two or 125 more cams having gear-teeth and dwell-places

- on their peripheries, a rotatable sliding shaft having thereon a check-drum, and a gear-section adapted to mesh with the gear-teeth on said cams, means to rotate said shaft, shifting mechanism for changing the vertical position of the shuttles, and connections between said shifting mechanism and said sliding shaft, to slide said shaft endwise, substantially as shown and described.
- 10 9. In a loom of the class described, mechanism to lift and lower the shuttle-rails and shuttles, and means controlled by said mechanism, to operate the said shuttles longitudinally, substantially as shown and described.
- 15 10. In a loom of the class described, lifting and lowering mechanism, consisting of vibrators, levers, and connectors, and means, controlled by said mechanism, to operate the shuttle-racks and shuttles longitudinally, substantially as shown and described.

11. The combination with two or more cams having gear-teeth and dwell-places on their peripheries, of a sliding shaft, a gear-section, and a dwell-section fast on said shaft, said gear-section and dwell-section adapted to engage with the gear-teeth and dwell-places on said cams, substantially as shown and described.

12. The combination with a rotary cam having teeth and dwell-places on its periphery, and a gear-section having a dwell-place thereon adapted to operate said cam, of means to slide said gear-section in and out of mesh with the teeth of said cam, substantially as shown and described.

EPPA H. RYON.
